Philip Beck

UNITED STATES PATENT OFFICE.

NORMAN H. WHITE, OF BROOKLINE, MASSACHUSETTS, ASSIGNOR TO AUTO VACUUM FREEZER COMPANY, INC., OF NEW YORK, N. Y., A CORPORATION OF NEW YORK.

COVER ATTACHMENT.

Application filed January 11, 1921. Serial No. 436,461.

To all whom it may concern:

Be it known that I, NORMAN H. WHITE, a citizen of the United States, and a resident of Brookline, in the county of Norfolk and State of Massachusetts, have invented certain new and useful Improvements in Cover Attachments, of which the following is a specification, reference being made to the accompanying drawings, forming a part thereof.

My invention relates to certain improvements in cover-attachments for containers and in fastening devices therefor, when such covers are employed as closure means, and the principal aim of my improvement is to provide a simple and efficient cover structure with fastening means for such cover to seal against leakage the oppositely-disposed openings within the re-entrant head ends formed in the type of ice-cream freezer set forth in the William B. McCann Patent No. 1,013,672 of January 2, 1912, where it is desirable that both the cover and its fastening means shall be contained within the depressed end space lying below the outer rim of the freezer.

A further object of my invention is to provide a cover-attachment which shall detachably, yet effectively, secure the cover on the openings so as to afford a tight joint while embodying therein a handle for the freezer which, when lifted, will not spring or loosen the parts which fasten the cover on the container openings thereby producing leakage. A further object is to simplify and cheapen the construction of such cover-attachments without loss of strength or efficiency in operation in forming a tight seal for container openings.

Further advantages and functions will hereinafter be more particularly set forth, and a preferred embodiment of my invention is illustrated in the accompanying drawings in which—

Figure 1 is a diagrammatic elevation view of the McCann ice-cream freezer the upper portion being shown in vertical section with my improved cover attachment locked in position;

Figure 2 is an enlarged detail sectional view taken on the line 2—2 of Figure 3 looking in the direction of the arrow; and

Figure 3 is a top plan view of the freezer structure with the cover-attachment in place.

Similar numerals refer to similar parts through the several figures.

Referring to the drawings, the outer wall 4 of the freezer is cylindrically formed and carries at either end the circular end portions 5 so bent and secured to the outer wall 4 to form the annular rim 6 on which the freezer stands. The end portions 5 are bent to shape within the rims 6 to provide re-entrant heads 7 to provide annular spaces 65 to contain the cover and attachment. Centrally located within the end portions 5 are openings 8 and 9, such openings being oppositely-disposed to each other. Surrounding the openings 8 and 9 are the annular beadings 10 preferably integrally formed in the end portions 5 as shown in Figure 1. The inner cylindrical wall 11 of the freezer structure is concentrically arranged within the outer wall 4 so as to afford an air-insulating space 12 throughout the exposed portion of the freezer except for the openings 8 and 9.

The cover 13 consists of a circular sheet-metal structure having a cylindrical depressed portion 14 formed therein, which portion is adapted to fit within the openings 8 and 9 as shown. The cover 13 also has the flat rim 15 surrounding the depressed portion 14, the rim 15 carrying on its underside the gasket 16 formed of rubber or other suitable material to coact with the annular beading 10 as shown in Figure 1. Extending diametrically across the depressed portion 14 is the flat cross-bar 17 rigidly secured to the rim 15 at diametrically opposite points which cross-bar has the flat end projections 18 and 19 which are adapted to engage within the continuous recessed channel members 20 and 21 diagonally arranged on the end portions 5 and secured thereto at both ends adjacent the openings 8 and 9 by the rivets 22 in a tangential position relatively to such openings, as shown in Figure 3.

As shown more particularly in Figure 2 the recessed channel members 20 and 21 are so shaped as to provide an inclined or beveled under surface 23 to engage with the cross-bar projections 18 and 19, the larger opening 24 relatively to the end portion 5 in the particular embodiment shown being formed in that end having the single rivet 22 to secure the recessed channel member to such end portion 5. The upper surface of

the flat projections 18 and 19 being inserted at the larger opening 24 as shown in dotted lines in Figure 2 slides to the left in this figure to the full-line position where it is frictionally held through the coaction of cover 13, cross-bar 17 and recessed channel members 20 and 21. The recessed channel openings 24 in the lug members 20 and 21 are arranged obliquely to radial lines across the cover openings 8 and 9 as shown in Fig. 3.

The operation of my cover-attachment is shown in Figure 3, and is substantially as follows: When the cover 13 is pressed into the openings 8 or 9 the cross-bar 17 should have the position shown in dotted lines outside the recessed channel members 20 and 21; the cover is then rotated in an anti-clockwise direction as indicated by the arrow, when the projections 18 and 19 will pass beneath the opening 24 and engage the inclined under surface 23. The cover 13 is then further rotated in the same direction which movement forces the cover downwardly into the openings, the gasket 16 forming a tight seal on the beading 10 preventing all leakage, while the frictional engagement of the cross-bar projections 18 and 19 in their progressively increasing surface engagement on the inclined under surface 23 of the continuous recessed channel members secured at either end to the end portions 5 provides a strong and unyielding closure for the openings 8 and 9, particularly when the freezer structure is lifted by using the cross-bar 17 as a handle.

I have discovered that the use of these continuous recessed channel members forms a simple yet exceptionally strong attachment for the cover while affording a lifting device for the freezer without in any way springing or loosening the parts or breaking the seal between the gasket and beading when the freezer is lifted by the cross-bar 17. It will be observed as well that such cover and its fastening devices are all contained within the re-entrant heads end of the freezer, which is essential since the freezer structure rests on the floor or other support on one of the circular end portions.

While I have shown and described my improvement as embodiment in an ice-cream freezer, I do not wish to restrict same to such use as it may be effectively employed in fastening covers to form a closure means for different forms of containers as will be readily understood by those skilled in the art.

I claim as my invention:

1. In a cover attachment, a rotatable circular cover, a clamping-bar having flat end projections secured rigidly and diametrically across the cover, said projections extending beyond the cover rim, a container having an annular reentrant head with an

inner concentric opening for the cover, and a pair of elongated and mutually parallel loop recessed channel members, each tangentially disposed adjacent said cover opening with its spaced-apart ends secured to said reentrant head, said members having their recessed channels arranged obliquely to radial lines across said cover opening, whereby said bar end projections when rotated slidingly engage said members with a mutually increasing surface to thereby frictionally hold said clamping-bar and cover in position on said opening.

2. In a cover attachment, a rotatable circular cover, a clamping-bar having flat end projections secured rigidly and diametrically across the cover, said projections extending beyond the cover rim, a container having an annular reentrant head with an inner concentric opening for the cover, and a pair of elongated and mutually parallel loop recessed channel members, each tangentially disposed adjacent said cover opening with its spaced-apart ends secured to said reentrant head, said members having their recessed channels arranged obliquely to radial lines across said cover opening, and provided also with inclined under surfaces oppositely disposed, whereby said bar end projections slidingly engage said members with a mutually increasing surface-to-surface contact to frictionally hold said clamping-bar and cover in position on said opening when said bar and cover are rotated.

3. In a cover attachment, a rotatable circular cover having a depressed portion inside an outer rim, a clamping bar having flat end projections secured rigidly to the rim and diametrically across the cover, said projections extending beyond the cover rim, a container having an annular reentrant head with an inner concentric opening for the cover, and a pair of straight elongated and mutually parallel loop recessed channel members, each tangentially disposed adjacent said cover opening with its spaced-apart ends secured to said reentrant head, said members having their recessed channels arranged obliquely to radial lines across said cover opening, whereby said bar end projections when rotated slidingly engage said members with a mutually increasing surface-to-surface contact to frictionally hold said clamping-bar and cover in sealing position on said opening.

4. In a cover attachment, a rotatable circular cover having a depressed portion inside an outer rim, a clamping-bar having flat end projections secured rigidly to the rim and diametrically across the cover, said projections extending beyond the cover rim, a container having an annular reentrant head with an inner concentric opening for the cover, and a pair of straight elongated

- and mutually parallel loop recessed channel members, each tangentially disposed adjacent said cover opening with its spaced-apart ends secured to said reentrant head, 6 said members having their recessed channels arranged obliquely to radial lines across said cover opening and provided also with inclined under surfaces oppositely disposed, whereby said bar end projections slidingly 10 engage said under surfaces with a mutually increasing surface-to-surface contact to frictionally hold said clamping-bar and cover in sealing position on said opening when said bar and cover are rotated.
- 15 5. In a cover-attachment, a rotatable circular cover, a clamping-bar rigidly secured diametrically thereto with flat end projections extending beyond the cover rim, a container having a circular reentrant cover opening, and a pair of straight mutually parallel loop recessed channel members, each 20 tangentially disposed adjacent said cover opening with its spaced-apart ends secured to said reentrant head, said members having their recessed channels arranged obliquely to radial lines across said cover-opening, whereby said bar end projections slidingly 25 engage said under surfaces with a mutually increasing surface-to-surface contact to inwardly force and frictionally hold said cover in said opening when the bar and cover are rotated in unison in a predetermined direction.
6. In a cover attachment, a rotatable circular cover, a clamping-bar rigidly secured 30 diametrically thereto with flat end projections extending beyond the cover rim, a container having a circular reentrant cover opening, and a pair of straight mutually parallel loop recessed channel members, each 35 tangentially disposed adjacent said cover opening with its spaced-apart ends secured to said reentrant head, said members having their recessed channels arranged obliquely to radial lines across said cover-opening, and provided also with oppositely extending inclined under surfaces, whereby said bar end projections slidingly engage said under surfaces with a mutually increasing surface-to-surface contact to inwardly force and 40 frictionally hold said cover in said opening when the bar and cover are rotated in unison in a predetermined direction.

NORMAN H. WHITE.
